Primary Examiner — Andrew T Nemeth

(57) **CLAIM**

The ornamental design for a hanging automatic pet water dispenser, as shown and described.

DESCRIPTION

FIG. 1 is a front, right and top perspective view of a hanging automatic pet water dispenser, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, left and bottom perspective view; and, FIG. 9 is a perspective view in the disassembled configuration thereof.

The broken lines shown in the drawings illustrate portions of the hanging automatic pet water dispenser that form no part of the claimed design.
